BED-MOTION FOR PRINTING-PRESSES.

No. 911,498.

Specification of Letters Patent.

Patented Feb. 2, 1909.

Application filed October 18, 1906. Serial No. 339,480.

To all whom it may concern:

Be it known that we, WILLIS K. HODGMAN and BICKNELL HALL, citizens of the United States, and residents of Taunton, in the county of Bristol and State of Massachusetts, have invented an Improvement in Bed-Motions for Printing-Presses, of which the following description, in connection with the accompanying drawings, is a specification, 10 like letters on the drawings representing like parts.

This invention relates to mechanism for converting rotary motion into rectilineal reciprocating motion, and is particularly designed for use in connection with the reciprocating beds of printing presses, though it may be applied and used in any location and for any purpose for which the same is adapted.

20 In order that the principles of the invention may be fully apparent, we have herein disclosed for illustrative purposes one type or embodiment of the invention in the accompanying drawings, it being understood 25 that the invention may be carried out by other embodiments thereof and by mechanism widely differing from that herein selected for illustration.

Having reference to that type of the invention herein illustrated in the drawings: 30 Figure 1 is a side elevation, with the base partly in section, of a single impression cylinder and a bed plate coöperating therewith and operated in accordance with our invention. Figure 2 is mainly a plan view of the parts embodying our invention beneath the upper rack of the bed-plate, the bearings, 35 portions of the framing and the bed reversing rack being shown in section, and, Figure 3 is a vertical section upon the line 3—3 of Fig. 1 of the type of operating mechanism herein selected for illustration, the reversing shaft being indicated in elevation and the impression cylinder and driving gear carried thereby being diagrammatically indicated.

Having reference to that type or embodiment of the invention herein chosen for the illustration, the bed of the printing-press is 50 indicated at 1, such bed being constructed in any suitable manner and operatively connected to mechanism to cause the continuously and uniformly running driving shaft, first, to propel the bed continuously and

at uniform speed in one direction, and then 55 to propel the bed continuously and at uniform speed in the opposite direction, and also to provide for the reversal movement of the bed at the end of its continuous and uniform movement in one direction, by 60 gradually slowing down said movement until the bed is brought to rest, and then gradually accelerating its movement in the opposite direction until it acquires the speed of its uniform stroke. 65

In the usual operation of a printing-press of the bed and cylinder type, the printing bed carrying the printing surface is reciprocated in the manner above stated, the periphery of the cylinder and paper thereon 70 traveling in the printing operation at the same surface speed as the printing surface on the bed, so that the paper is pressed against the printing surface with a rolling action and without any slip of one surface 75 relative to the other along the line of contact between the cylinder and printing surface. In this type of press the impression is commonly taken only in the travel of the bed in one direction under the cylinder, which continues to run in the same direction all the 80 time that the press is in operation, and after the bed has made its forward and working movement or stroke under the cylinder the bed must be returned past the cylinder to 85 the starting point preparatory for another working stroke. In the return movement of the bed the cylinder is commonly raised a little, so that its surface is entirely above and clear of the printing surface on the bed, 90 which is now traveling in an opposite direction to the surface of the cylinder, which thus makes an idle revolution during the return or non-working stroke of the bed.

Generally speaking, the mechanism for 95 driving the bed of such type of printing presses comprises a continuously rotating toothed gear and two racks connected with the printing bed so as to be positioned adjacent opposite edges of the gear, and means 100 to cause engagement of one of the racks with said gear, to produce the principal part of a stroke in one direction, and to cause the engagement of the other rack with the gear, to produce the principal part of the stroke 105 in the other direction, the bed commonly running at uniform speed throughout the part of its stroke effected by the rack and

gear, this being the same as the surface speed of the cylinder during the stroke.

When the bed arrives at the end of such rack and gear movement, it comes under the control of another part of the bed motion, which may be termed the reversing mechanism, and which acts to bring the bed to a stop at the end of a short movement beyond the rack traveling movement, and to start the bed in the reverse direction and bring it to the velocity of the rack driven movement by the time that the second rack arrives at and comes into engagement with the gear, at which time the reversing mechanism gives up control and the bed is again driven by the rack and gear movement to the point near the other end of its stroke, where the reversing mechanism again takes control and performs a similar reversal of the movement of the bed to that just described. That is to say, the reversing mechanism is designed to take the bed at full working speed, reduce its velocity by gradual diminution, until it is stopped and then move it in the opposite direction with a gradual acceleration until it is brought up to full working velocity in said opposite direction.

In such type of mechanism the gear and the racks may be relatively shifted in many different ways, among which may be enumerated the following: The racks may be opposed in the same vertical plane and the gear may be shifted vertically to engage the racks in alternation, or the racks may be opposed in different vertical planes and the gear be shifted laterally from engagement with one rack to engagement with the other, or the relative movement may be accomplished by maintaining the gear stationary and bringing the racks alternately into engagement therewith by vertical or lateral movement. The racks and gear may be otherwise opposed or arranged to accomplish the same result.

Our invention is applicable to a gear and rack mechanism wherein the relative movement of said gear and racks is accomplished in any of the above indicated ways or in any other desired manner. Although that type or embodiment of the invention selected for illustration discloses merely a gear adapted to be vertically shifted into engagement with racks in the same vertical plane, the principles of the invention may be carried out in other ways.

A printing or impression cylinder is indicated at 2, said cylinder being driven in any preferred manner (Fig. 3) by a gear 3 at one end thereof, meshing with a gear 4 upon a reversing shaft 5, mounted in suitable bearings 6-6 in the frame-work of the machine, said frame-work supporting therein tracks or ways 7, 8 and 9, preferably having sets of rollers 10, 11 and 12, receiving the bed 1.

The lower face of the bed-plate 1 is provided (Figs. 1 and 3) with an upper rack 13, and a lower rack 14, herein shown as facing each other and adapted to receive between them a pinion 15, said lower rack 70 being positioned above the reversing shaft 5. Since in the present type of the invention said racks are shown as stationary and the relative movement between the pinion and racks is obtained by a shifting movement 75 of said pinion, herein shown as a vertical shifting movement, said pinion 15 is so mounted as to be brought alternately into working relation with the upper and lower racks. 80

Heretofore, so far as we are aware, in that type of press wherein racks are employed, the teeth whereof substantially face each other, the lower rack has been arranged below the reversing gear, so that said rack 85 engages said gear at the lower edge of the gear. Such a construction is objectionable in that the weight of the press is largely increased by the length of parts required to support the lower rack beneath the reversing 90 gear, and furthermore, a compactness of structure, such as is procured according to our invention, cannot be secured, such former types of presses being necessarily high framed. By supporting both racks above 95 the reversing shaft, it is possible not only to greatly diminish the vertical length of its parts required for the support of the lower rack, but the supports may be more lightly constructed, while still securing a firm and 100 effective positioning for the parts.

Since in the present type of the invention the lower rack is located above the reversing shaft, and since in such type of the invention said racks are arranged with their teeth facing each other, said racks are not engaged by a gear directly mounted upon the reversing shaft, but by any preferred form or type of mechanism, preferably receiving motion from said reversing shaft. 110 While such mechanism may be of any desired type, in the present instance the reversing shaft is shown as provided with a bed reciprocating gear 16, to which motion may be imparted in any desired manner, 115 (Figs. 1 and 2) as by a pinion 17 upon a driving shaft 18, suitably supported in the frame-work of the machine. Preferably mounted upon the reversing shaft 5 or concentric therewith, and as herein shown upon the hub of gear 16, is a bell-crank lever 19, the upper arm 20 whereof carries the pinion 15, which in the present type of the invention is shown as meshing with the gear 16 to receive a continuous movement of rotation, it being herein shown as shifted from one rack to the other by movement of the bell-crank lever 19, for which purpose the lower arm 21 may be provided with a roll 22, engaging a cam track 23 in one face of 130 120 125

a cam 24, mounted upon a shaft 25 suitably supported in the frame-work of the machine, said shaft being driven in any desired manner, at the proper speed. It is of course apparent that any suitable type of mechanism may be employed to shift the said pinion 15, provided the relative movement between the pinion and the racks be obtained by a movement of the pinion. The said pinion 15 is preferably so mounted upon the arm 20 of the bell-crank lever 19 as to be constantly maintained in meshing engagement with the gear 16, and thus to be at all times rotated thereby, it rolling thereon when shifted from one rack to the other, and being sufficiently wide, as indicated in Fig. 2, simultaneously to engage both the gear 16 and one or the other of said racks. Since said pinion 15 is, in the present type of the invention, at all times in mesh with the gear 16, there is no possibility of failure of said pinion accurately to mesh with each rack when shifted for engagement therewith.

During the engagement of the pinion 15 with either rack, the bed of the press is driven at a uniform speed in one direction or the other. In the present type of the invention the parts are so proportioned as that one rotation of bed reciprocating gear 16, and consequently four rotations of pinion 15 occur during the period of the engagement with said pinion 15 with either rack. As the bed nears its limit of movement in either direction, mechanism is brought into play to control the movement of the bed during the shifting of pinion 15 from one rack to the other, such mechanism preferably being such as to receive the bed at its full speed of movement, gradually to diminish such rate of speed until the bed is brought to a stop and then to drive the bed in the opposite direction at a gradually increasing speed until the working speed of the bed is reached, at which time the bed is again brought under the control of pinion 15.

While any suitable mechanism may be employed to control the bed during the shifting of the pinion 15, we have in the present type of the invention indicated for that purpose (Figs. 1 and 2) reversing gears 26 and 27 mounted respectively in the outer forked ends of arms 28 and 29, which outer ends therefore provide movable fulcras for said gears, the inner ends of said arms being forked as indicated at 30 and 31, to constitute straps suitably connected to yokes 30' and 31' mounted as shown upon eccentricities 32 and 33 herein shown as mounted upon the reversing shaft 5, upon either side of a short bed reversing rack 34, with which the reversing gears 26 and 27 are adapted to be brought alternately into engagement. Suitably supported in the frame-work of

the machine (Fig. 1) are stationary reversing racks 35 and 36, upon which said reversing gears 26 and 27 are constantly reciprocated during the operation of the press through the described eccentric connections.

The reversing shaft 5 in the present type of the invention carries the primary reversing element or elements shown in the present embodiment of the invention to be the eccentricities 32, 32. It is course apparent that other types or embodiments of reversing elements may be employed and carried by said reversing shaft and we are in no sense to be limited to the particular type and embodiment shown and described.

Considering the type of mechanism shown, as the bed 1 nears its limit of travel to the right, the bed reversing rack 34 is brought into engagement with the reversing gear 26, at which time the shifting movement of pinion 15 commences, the said gear 26 being rotated because of its meshing engagement with the frame reversing rack 35 and the eccentric connection with the reversing shaft 5, the eccentric connection being such that under the control of said gear 26, the movement to the right of said bed is gradually reduced to zero, and then gradually augmented in an opposite direction until the full working speed of the bed has been secured, at which time the pinion 15 has been brought into meshing relation with the other bed rack, the bed then passing from the control of gear 26 to the control of pinion 15. As the bed nears the end of its movement in the opposite direction, a similar operation occurs through the instrumentality of the bed reversing rack 34, the frame reversing rack 36 and the gear 27. With the proportion of parts herein indicated one-half rotation of gear 16 occurs during each reversing movement of the bed. It is apparent, however, that the proportioning and timing of the various parts may be varied as desired. While the extent of the shifting movement of gear 15 may be varied as desired, in the present type of the invention it may be noted that a movement of pinion 15 equaling one pitch thereof is sufficient to carry the same from engagement with one rack to engagement with the other.

Having thus described one type or embodiment of the invention, it is to be understood that although the mechanism illustrated has been specifically referred to, descriptive terms are employed, not in their subordinate, but in their general sense and for descriptive purposes merely, and that the scope of the invention is set forth in the following claims:

We claim—

1. A printing press having a reciprocable bed carrying opposed racks, a reversing

- 1 shaft located below said racks, a bed reciprocating gear carried by said reversing shaft, a pinion meshing with said bed reciprocating gear, and rotary movement imparting means whereby engagement is effected in alternation between said racks and said pinion.
2. A printing press having a reciprocable bed carrying opposed racks, a reversing shaft located below said racks having thereon a primary reversing element and a rack driving pinion oppositely rotated with respect to said reversing shaft, and pinion revolving mechanism to roll said pinion from engagement with one rack to engagement with another.
3. A printing press having a reciprocable bed carrying opposed racks, a reversing shaft located below said racks, a rack driving pinion oppositely rotated with respect to said reversing shaft, pinion shifting mechanism to shift said pinion from engagement with one rack to engagement with another and eccentrically actuated reversing gears actuated from said reversing shaft and adapted alternately to be brought into driving relation to said bed to reverse the movement thereof at the end of each stroke thereof and means other than said reversing shaft to rotate said gears.
4. A printing press having a reciprocable bed carrying opposed racks, a reversing shaft located below said racks, a rack driving pinion oppositely rotated with respect to said reversing shaft, pinion shifting mechanism to shift said pinion from engagement with one rack to engagement with another and eccentrically actuated reversing gears actuated from said reversing shaft and adapted alternately to be brought into driving relation to said bed to reverse the movement thereof at the end of each stroke thereof, and stationary means to rotate said gears.
5. A printing press having a reciprocable bed carrying opposed racks, a reversing shaft located below said racks, a rack driving pinion oppositely rotated with respect to said reversing shaft, pinion shifting mechanism to shift said pinion from engagement with one rack to engagement with another and eccentrically actuated reversing gears actuated from said reversing shaft and adapted alternately to be brought into driving relation to said bed to reverse the movement thereof at the end of each stroke thereof, said gears each having a movable fulcrum.
6. A printing press having a reciprocable bed carrying opposed racks, a reversing shaft located below said racks, a rack driving pinion oppositely rotated with respect to said reversing shaft, pinion shifting mechanism to shift said pinion from engagement with one rack to engagement with another, reversing gears, arms mounted upon said reversing shaft and supporting said gears for rotation thereon, said gears being adapted alternately to be brought into driving relation to said bed to reverse the movement thereof at the end of each stroke thereof. 70
7. A printing press having a reciprocable bed carrying opposed racks, a reversing shaft located below said racks having thereon a primary reversing element and a bed reciprocating gear carried by said reversing shaft, a pinion meshing with said bed reciprocating gear, and pinion elevating and depressing mechanism to shift said pinion into engagement with said racks in alternation. 75
8. A printing press having a reciprocable bed carrying opposed racks, a reversing shaft located below said racks having thereon a primary reversing element, a bed reciprocating gear carried by said reversing shaft, a pinion meshing with said bed reciprocating gear and adapted by rolling engagement with said bed reciprocating gear to be brought into engagement with said racks in alternation, and mechanism to 80 part said rolling movement. 85
9. A printing press having a reciprocable bed carrying opposed racks, a reversing shaft located below said racks having thereon a primary reversing element, a rack driving pinion adapted to be brought into engagement with said racks in alternation by movement of revolution about a center and rotation upon its axis, and means to impart said described movements of revolution and rotation. 90
10. A printing press having a reciprocable bed carrying opposed racks, a reversing shaft below said racks and having thereon a primary reversing element, a rack driving pinion adapted to be brought into engagement with said racks in alternation by movement of revolution about a center and rotation upon its axis and means intermediate said reversing shaft and said pinion to impart said described movements of revolution and rotation. 105
11. A printing press having a reciprocable bed carrying opposed racks, a reversing shaft located below said racks and having thereon a primary reversing element, a rack driving pinion rotated by said reversing shaft, and means to shift said pinion from engagement with one rack to engagement with an opposed rack by a rolling movement 110 of said pinion. 115
12. A printing press having a reciprocable bed carrying opposed racks, a reversing shaft located below said racks and having thereon a primary reversing element, a rack driving pinion rotated by said reversing shaft and mounted for swinging movement thereon and means to swing said pinion from engagement with one rack to engagement with an opposed rack. 120 125

13. A printing press having a reciprocable bed carrying opposed racks, a reversing shaft located below said racks and having thereon a primary reversing element, a lever concentric with the reversing shaft, a rack driving pinion carried by said lever, and actuating means for said lever whereby said pinion is shifted from engagement with one rack to engagement with an opposed rack.
14. A printing press having a reciprocable bed carrying opposed racks, a reversing shaft located below said racks and having a primary reversing element, a bell crank lever concentric with said reversing shaft, a pinion carried by said bell crank lever and means to actuate said lever, thereby to move said pinion from engagement with one rack to engagement with an opposed rack.
15. A printing press having a reciprocable bed carrying opposed racks, a reversing shaft having thereon a primary reversing element, a lever concentric with said reversing shaft, a pinion carried by said lever and cam mechanism in engagement with said lever and adapted to swing the same to shift said pinion from engagement with one rack to engagement with an opposed rack.
16. A printing press having a reciprocable bed carrying opposed racks, a reversing shaft located below said racks and having thereon a primary reversing element, and a bed reciprocating gear carried thereby, a lever mounted on said reversing shaft, a pinion carried by said lever and in mesh with said bed reciprocating gear, and lever actuating mechanism to shift said pinion from engagement with one rack to engagement with an opposed rack.
17. A printing press having a reciprocable bed carrying opposed racks, a reversing shaft located below said racks and having thereon a primary reversing element, a bed reciprocating gear mounted upon said reversing shaft, a bell crank lever concentric with said reversing shaft, a pinion carried by said lever and meshing with said bed reciprocating gear, and lever actuating mechanism to shift said pinion from engagement with one rack to engagement with an opposed rack.
18. A printing press having a reciprocable bed carrying opposed racks, a reversing shaft located below said racks and having thereon a primary reversing element, a bed reciprocating gear mounted upon said reversing shaft, a bell crank lever concentric with said reversing shaft, a pinion carried by said lever and meshing with said bed reciprocating gear, and cam mechanism operating said lever, thereby to shift said pinion from engagement with one rack to engagement with an opposed rack.
19. A printing press having a reciprocable bed carrying a plurality of racks, a reversing shaft located below said racks and having thereon a primary reversing element, a rack driving pinion having a movement of revolution with respect to said shaft and of rotation upon its axis, and mechanism to impart said described movements to said pinion thereby to shift the same from one rack to another to drive said racks in alternation.
20. A printing press having a reciprocable bed carrying a plurality of racks, a reversing shaft located below said racks and having thereon a primary reversing element, a rack driving pinion rotated by said reversing shaft, and having means to revolve said pinion, thereby to roll said pinion from engagement with one rack to engagement with another.
21. A printing press having a reciprocable bed carrying a plurality of racks, a reversing shaft located below said racks, and having thereon a primary reversing element, a bed reciprocating gear carried by said reversing shaft, a pinion rotated by said bed reciprocating gear and pinion revolving mechanism acting thereby to roll said pinion from engagement with one rack to engagement with another.
22. A printing press having a reciprocable bed carrying a plurality of racks, a reversing shaft located below said racks and having thereon a primary reversing element, a rack driving pinion rotated by said reversing shaft, and means to shift said pinion from engagement with one rack to engagement with another rack by a rolling movement of said pinion.
23. A printing press having a reciprocable bed carrying a plurality of racks, a reversing shaft located below said racks and having thereon a primary reversing element, a rack driving pinion rotated by said reversing shaft, and means to move said pinion in an arc about a predetermined center from engagement with one rack to engagement with another rack and a gear upon said reversing shaft, the axis of said gear corresponding to the center of the said arc.
24. A printing press having a reciprocable bed carrying a plurality of racks, a reversing shaft located below said racks and having thereon a primary reversing element, and a rack driving pinion rotated by said reversing shaft, and means to move said pinion in an arc about said reversing shaft as a center from engagement with one rack to engagement with another rack.
25. A printing press having a reciprocable bed carrying a plurality of racks, a reversing shaft located below said racks, a rack driving pinion actuated from said reversing shaft, relative movement imparting devices to cause engagement of said rack driving pinion and said racks in alternation, and reversing gears operatively connected to said reversing shaft and adapted alternately to be brought into driving relation to said bed to reverse the

movement thereof at the end of each stroke each of said reversing gears having a movable fulcrum.

26. A printing press having a reciprocable bed carrying a plurality of racks, a reversing shaft located below said racks, a rack driving pinion actuated from said reversing shaft, relative movement imparting devices to cause engagement of said rack driving pinion and 5 said racks in alternation and reversing gears having speed diminishing and accelerating connections with said reversing shaft and adapted alternately to be brought into driving relation to said bed to reverse the movement thereof at the end of each stroke each of said reversing gears having a movable fulcrum.

27. A printing press having a reciprocable bed carrying a plurality of racks, a reversing shaft located below said racks, a rack driving pinion actuated from said reversing shaft, relative movement imparting devices to cause engagement of said rack driving pinion and 10 said racks in alternation, and reversing gears having eccentric connections with said reversing shaft and adapted alternately to be brought into driving relation to said bed to reverse the movement thereof at the end of each stroke and racks to rotate said reversing gears.

28. A printing press having a reciprocable bed carrying a plurality of racks, a reversing shaft located below said racks, a rack driving pinion actuated from said reversing shaft, relative movement imparting devices to cause 15 engagement of said rack driving pinion and said racks in alternation, and reversing gears each having a double yoke, and eccentric connection to said reversing shaft and adapted alternately to be brought into driving relation to said bed to reverse the movement thereof at the end of each stroke.

29. A printing press having a reciprocable bed carrying a plurality of opposed racks, a reversing shaft located below said racks, a 20 rack driving pinion actuated from said reversing shaft, relative movement imparting devices to cause engagement of said rack driving pinion and said racks in alternation, and reversing gears operatively connected to said reversing shaft and adapted alternately to be brought into driving relation to said bed to reverse the movement thereof at the end of each stroke said gears being bodily movable.

30. A printing press having a reciprocable bed carrying a plurality of opposed racks, a reversing shaft located below said racks, a rack driving pinion actuated from said reversing shaft, relative movement imparting 25 devices to cause engagement of said rack driving pinion and said racks in alternation and reversing gears having speed diminishing and accelerating connections with said reversing shaft and adapted alternately to

be brought into driving relation to said bed 65 to reverse the movement thereof at the end of each stroke said gears being bodily movable.

31. A printing press having a reciprocable bed carrying a plurality of opposed racks, a reversing shaft located below said racks, a 70 rack driving pinion actuated from said reversing shaft, relative movement imparting devices to cause engagement of said rack driving pinion and said racks in alternation, and reversing gears having eccentric connections with 75 said reversing shaft and adapted alternately to be brought into driving relation to said bed to reverse the movement thereof at the end of each stroke, and movable members mounted upon said reversing shaft, said gears being pivotally mounted upon said members and moving therewith.

32. A printing press having a reciprocable bed carrying a plurality of opposed racks, a reversing shaft located below said racks, a 80 rack driving pinion actuated from said reversing shaft, shifting mechanism to shift said pinion from engagement with one rack to engagement with an opposed rack and reversing gears adapted alternately to be 85 brought into driving relation to said bed to reverse the movement thereof at the end of each stroke, and movable members mounted upon said reversing shaft, said gears being pivotally mounted upon said members and 90 moving therewith.

33. A printing press having a reciprocating bed carrying opposed racks, a reversing shaft located below said racks, a rack driving pinion actuated from said reversing 100 shaft, pinion shifting means to shift said pinion into engagement with opposed racks in alternation and bodily movable reversing pinions operatively connected to said shaft and adapted alternately to be brought into driving relation to said bed to reverse the movement thereof at the end of each stroke.

34. A printing press having a reciprocable bed carrying opposed racks, a reversing shaft located below said racks, carrying a 110 bed reciprocating gear, a rack driving pinion in mesh with said bed reciprocating gear, pinion shifting mechanism to shift said pinion into alternate engagement with opposed racks, and bodily movable reversing pinions operatively connected to said shaft and adapted alternately to be brought into driving relation to said bed to reverse the movement thereof at the end of each stroke.

35. A printing press having a reciprocable bed carrying opposed racks, a reversing shaft located below said racks, carrying a bed reciprocating gear, a rack driving pinion in mesh with said bed reciprocating 115 gear, pinion shifting mechanism to shift said pinion into alternate engagement with opposed racks, and reversing gears eccentrically connected to said shaft and adapted 125

alternately to be brought into driving relation to said bed to reverse the movement thereof at the end of each stroke each of said gears being mounted upon a movable fulcrum.

36. A printing press comprising an impression cylinder having a gear, a reciprocable bed carrying a plurality of opposed racks, a reversing shaft having thereon a primary reversing element and carrying a gear in mesh with said impression cylinder gear, a bed reciprocating gear carried by said reversing shaft, a rack driving pinion rotated by said bed reciprocating gear, and pinion shifting mechanism to shift said pinion into alternate engagement with said opposed racks.

37. A printing press comprising an impression cylinder having a gear, a reciprocable bed carrying a plurality of opposed racks, a reversing shaft below said racks and having a gear in mesh with said impression cylinder gear, a bed reciprocating gear upon said reversing shaft, a rack driving pinion in mesh with said bed reciprocating gear, and pinion shifting mechanism to shift said pinion into alternate engagement with opposed racks while maintaining it in mesh with said bed reciprocating gear.

38. A printing press comprising an impression cylinder having a gear, a reciprocable bed carrying a plurality of opposed racks, a reversing shaft having a gear in mesh with said impression cylinder gear, a bed reciprocating gear upon said reversing shaft, a rack driving pinion in mesh with said bed reciprocating gear, and pinion shifting mechanism to shift said pinion into alternate engagement with opposed racks while maintaining it in mesh with said bed reciprocating gear.

39. A printing press having a reciprocable bed carrying opposed racks, a reversing shaft located below said racks, a bed reciprocating gear carried by said shaft, a rack driving pinion in mesh with said bed reciprocating gear, pinion shifting mechanism to shift said pinion into alternate engagement with opposed racks, eccentric mounts ed upon said reversing shaft and reversing gears operatively connected to said eccentricities and adapted alternately to be brought into driving relation to said bed to reverse the movement thereof at the end of each stroke.

40. A printing press having a reciprocable bed carrying opposed racks, a reversing shaft located below said racks, a bed reciprocating gear upon said shaft, a rack driving pinion in mesh with said bed reciprocating gear, shifting mechanism to shift said pinion into alternate engagement with opposed racks while maintaining the same in mesh with said gear, eccentricities upon said reversing shaft, and reversing

gears operatively connected to said reversing shaft and adapted alternately to be brought into driving relation to said bed to reverse the movement thereof at the end of each stroke.

41. A printing press having a reciprocable bed carrying opposed racks, a reversing shaft located below said racks, a rack driving pinion actuated from said reversing shaft, pinion shifting mechanism to shift said pinion into alternate engagement with opposed racks, a bed reversing rack carried by the bed, a plurality of stationary reversing racks, and reversing gears operatively connected with said reversing shaft and in engagement with said stationary racks respectively and adapted alternately to be brought into engagement with said bed reversing rack thereby to reverse the movement of said bed at the end of each stroke.

42. A printing press having a reciprocable bed carrying a plurality of opposed racks, a reversing shaft carrying a bed reciprocating gear, a rack driving pinion actuated by said gear, shifting mechanism to shift said pinion into alternate engagement with opposed racks, a bed reversing rack carried by said bed, a pair of stationary reversing racks, a pair of reversing gears in mesh with said stationary racks respectively and driving connections therefrom to said reversing shaft whereby when said gears are brought into engagement with said bed reversing rack at the end of opposite strokes the movement of the bed is reversed.

43. A printing press comprising an impression cylinder having a gear, a reciprocable bed carrying a plurality of racks, a reversing shaft having a gear thereon in mesh with said impression cylinder gear, a bed reciprocating gear, a rack driving pinion actuated by said gear, pinion shifting mechanism to shift said pinion into alternate engagement with said racks, and reversing gears operatively connected to said reversing shaft and adapted alternately to be brought into driving relation to said bed to reverse the movement thereof at the end of each stroke.

44. A printing press comprising an impression cylinder having a gear, a reciprocable bed carrying a plurality of racks, a reversing shaft having a gear thereon in mesh with said impression cylinder gear, a bed reciprocating gear upon said reversing shaft, a rack driving pinion actuated by said bed reciprocating gear, pinion shifting mechanism to shift said pinion into alternate engagement with said racks, reversing gears having eccentric connections with said reversing shaft and adapted alternately to be brought into driving relation to said bed to reverse the movement thereof at the end of each stroke.

45. A printing press having a reciprocable bed carrying a plurality of opposed racks, a reversing shaft located below said racks and carrying a bed reciprocating gear, a lever concentric with said reversing shaft, a rack driving pinion mounted upon said lever and in mesh with said bed reciprocating gear, lever actuating means to shift said pinion into alternate engagement with said racks, reversing gears operatively connected to said reversing shaft and adapted alternately to be brought into driving relation to said bed to reverse the movement thereof at the end of each stroke.
46. A printing press having a reciprocable bed carrying a plurality of opposed racks, a reversing shaft located below said racks and carrying a bed reciprocating gear, a lever concentric with said reversing shaft, a rack driving pinion mounted upon said lever and in mesh with said bed reciprocating gear, lever actuating means to shift said pinion into alternate engagement with said racks, reversing gears eccentrically connected to said reversing shaft and adapted alternately to be brought into driving relation to said bed to reverse the movement thereof at the end of each stroke.
47. A printing press having a reciprocable bed carrying opposed racks, a reversing shaft located below said racks and carrying a bed reciprocating gear, a lever mounted upon said reversing shaft, a rack driving pinion concentric with said lever and rotated by said bed reciprocating gear, cam mechanism to operate said lever thereby to shift said pinion into alternate engagement with said racks, and reversing gears operatively connected to said reversing shaft and adapted alternately to be brought into driving relation to said bed to reverse the movement thereof at the end of each stroke.
48. A printing press having a reciprocable bed carrying opposed racks, a reversing shaft located below said racks and carrying a bed reciprocating gear, a lever concentric with said reversing shaft, a rack driving pinion mounted upon said lever and rotated by said bed reciprocating gear, cam mechanism to operate said lever thereby to shift said pinion into alternate engagement with said racks, and reversing gears eccentrically connected to said reversing shaft and adapted alternately to be brought into driving relation to said bed to reverse the movement thereof at the end of each stroke.
49. A printing press having a reciprocable bed carrying opposed racks, a reversing shaft located below said racks and carrying a bed reciprocating gear, a lever concentric with said reversing shaft, a rack driving pinion mounted upon said lever and rotated by said bed reciprocating gear, cam mechanism to operate said lever thereby to shift said pinion into alternate engagement with
50. A printing press comprising an impression cylinder having a gear, a reciprocable bed carrying a plurality of opposed racks, a reversing shaft having thereon a primary reversing element and located below said racks and carrying a gear in mesh with said impression cylinder gear, a bed reciprocating gear carried by said reversing shaft, a rack driving pinion rotated by said bed reciprocating gear, and pinion shifting mechanism to shift said pinion into alternate engagement with said opposed racks.
51. A printing press comprising an impression cylinder having a gear, a reciprocable bed carrying a plurality of opposed racks, a reversing shaft below said racks and having a gear in mesh with said impression cylinder gear, a bed reciprocating gear upon said reversing shaft, a rack driving pinion in mesh with said bed reciprocating gear, pinion shifting mechanism to shift said pinion into alternate engagement with said opposed racks while maintaining it in mesh with said bed reciprocating gear, and reversing means operatively connected to said reversing shaft and adapted alternately to be brought into driving relation to said bed to reverse the movement thereof at the end of each stroke.
52. A printing press comprising an impression cylinder having a gear, a reciprocable bed carrying a plurality of opposed racks, a reversing shaft having a gear in mesh with said impression cylinder gear, a bed reciprocating gear upon said reversing shaft, a rack driving pinion in mesh with said bed reciprocating gear, pinion shifting mechanism to shift said pinion into alternate engagement with said opposed racks while maintaining it in mesh with said bed reciprocating gear, and reversing gears operatively connected to said reversing shaft and adapted alternately to be brought into driving relation to said bed to reverse the movement thereof at the end of each stroke.
53. A printing press comprising an impression cylinder having a gear, a reciprocable bed carrying a plurality of opposed racks, a reversing shaft below said racks and having a gear in mesh with said impression cylinder gear, a bed reciprocating gear upon said reversing shaft, a rack driving pinion in mesh with said bed reciprocating gear, pinion shifting mechanism to shift said pinion into alternate engagement with opposed

racks while maintaining it in mesh with said bed reciprocating gear, and reversing gears eccentrically connected to said reversing shaft and adapted alternately to be brought into driving relation to said bed to reverse the movement thereof at the end of each stroke.

54. A printing press comprising an impression cylinder having a gear, a reciprocable bed carrying a plurality of opposed racks, a reversing shaft having a gear in mesh with said impression cylinder gear, a bed reciprocating gear upon said reversing shaft, a rack driving pinion in mesh with

10 said bed reciprocating gear, pinion shifting mechanism to shift said pinion into alternate engagement with opposed racks while maintaining it in mesh with said bed reciprocating gear, and reversing gears eccentrically connected to said reversing shaft and adapted alternately to be brought into driving relation to said bed to reverse the movement thereof at the end of each stroke.

55. A printing press comprising an impression cylinder having a gear, a reciprocable bed carrying a plurality of opposed racks, a reversing shaft below said racks and having a gear in mesh with said impression cylinder gear, a bed reciprocating gear upon 25 said reversing shaft, a rack driving pinion in mesh with said bed reciprocating gear, pinion shifting mechanism to shift said pinion into alternate engagement with opposed racks while maintaining it in mesh with 30 said bed reciprocating gear, eccentrically mounted upon said reversing shaft, and reversing gears actuated by said eccentric and adapted to be brought into driving relation to said bed to reverse the movement thereof at the end of each stroke.

56. A printing press comprising an impression cylinder having a gear, a reciprocable bed carrying a plurality of opposed racks, a reversing shaft having a gear in 45 mesh with said impression cylinder gear, a bed reciprocating gear upon said reversing shaft, a rack driving pinion in mesh with said bed reciprocating gear, pinion shifting mechanism to shift said pinion into alternate engagement with opposed racks while maintaining it in mesh with 50 said bed reciprocating gear, eccentrically mounted upon said reversing shaft, and reversing gears actuated by said eccentric and adapted to be brought into driving relation to said bed to reverse the movement thereof at the end of each stroke.

57. A printing press comprising an impression cylinder having a gear, a reciprocable bed carrying a plurality of opposed racks, a reversing shaft below said racks and having a gear in mesh with said impression cylinder gear, a bed reciprocating gear upon said reversing shaft, a rack driving pinion in mesh with said bed reciproc-

cating gear, pinion shifting mechanism to shift said pinion into alternate engagement with opposed racks while maintaining it in mesh with said reciprocating gear, a bed reversing rack carried by said bed, a plurality of stationary reversing racks, eccentrically mounted upon said reversing shaft, and reversing gears operatively connected to said eccentric, in mesh with said stationary reversing racks respectively, and adapted to be brought alternately into engagement with said bed reversing racks thereby to reverse the movement of the bed at the end of each stroke thereof.

58. A printing press comprising an impression cylinder having a gear, a reciprocable bed carrying a plurality of opposed racks, a reversing shaft having a gear in mesh with said impression cylinder gear, a bed reciprocating gear upon said reversing shaft, a rack driving pinion in mesh with said bed reciprocating gear, pinion shifting mechanism to shift said pinion into alternate engagement with opposed racks while maintaining it in mesh with said reciprocating gear, a bed reversing rack carried by said bed, a plurality of stationary reversing racks, eccentrically mounted upon said reversing shaft, and reversing gears operatively connected to said eccentric, in mesh with said stationary reversing racks respectively, and adapted to be brought alternately into engagement with said bed reversing racks thereby to reverse the movement of the bed at the end of each stroke thereof.

59. A printing press having a reciprocable bed carrying opposed racks, a reversing shaft located below said racks, a bed reciprocating gear carried by said reversing shaft, a pinion meshing with said bed reciprocating gear, and pinion elevating and depressing mechanism to shift said pinion into engagement with said racks in alternation.

60. A printing press having a reciprocable bed carrying opposed racks, a reversing shaft located below such racks, a rack driving pinion oppositely rotated with respect to said reversing shaft, relative movement imparting means to impart relative movement to said rack driving pinion and said racks, reversing gears adapted alternately to be brought into driving relation to said bed to reverse the movement thereof at the end of each stroke thereof, each of said gears having a movable fulcrum.

61. A printing press having a reciprocable bed carrying opposed racks, a reversing shaft located below said racks, a rack driving pinion oppositely rotated with respect to said reversing shaft, relative movement imparting means to impart relative movement to said rack driving pinion and said racks, reversing gears adapted alternately to be brought into driving relation to said

bed to reverse the movement thereof at the end of each stroke thereof, and rack mechanism to rotate said gears.

62. A printing press having a reciprocable bed carrying opposed racks, a reversing shaft located below said racks, an impression cylinder having a gear thereon, said reversing shaft carrying a gear in mesh with the gear of the said impression cylinder, a primary reversing member upon said reversing shaft, a bed reciprocating gear upon said reversing shaft between said primary reversing member and said gear in mesh with the impression cylinder gear, and a rack driving gear driven from said bed reciprocating gear and means relatively to shift said opposed racks and said gear thereby to bring alternate racks into engagement with said gear.

63. A printing press having a reciprocable bed carrying opposed racks, a reversing shaft located below said racks, an impression cylinder having a gear thereon, said reversing shaft carrying a gear in mesh with the gear of the said impression cylinder, a primary reversing member upon said reversing shaft, a bed reciprocating gear upon said reversing shaft between said primary reversing member and said gear in mesh with the impression cylinder gear, a rack driving pinion meshing with said bed reciprocating gear, and means to impart relative movement to said pinion and said racks whereby the racks may be engaged with said pinion alternately.

64. A printing press having a reciprocable bed carrying opposed racks, a reversing shaft located below said racks, an impression cylinder having a gear thereon, said reversing shaft carrying a gear in mesh with the gear of the said impression cylinder, a primary reversing member upon said reversing shaft, a bed reciprocating gear upon said reversing shaft between said primary reversing member and said gear in mesh with the impression cylinder gear, a rack driving pinion driven from said bed reciprocating gear, and means to shift said pinion into alternate engagement with said racks.

65. A printing press having a reciprocable bed carrying opposed racks, a reversing shaft located below said racks, an impression cylinder having a gear thereon, said reversing shaft carrying a gear in mesh with the gear of the said impression cylinder, a primary reversing member upon said reversing shaft, a bed reciprocating gear upon said reversing shaft between said primary reversing member and said gear in mesh with the impression cylinder gear, a rack driving pinion meshing with said bed reciprocating gear, and means to elevate and depress said pinion thereby to bring it

into alternate engagement with said opposed racks.

66. A printing press having a reciprocable bed carrying opposed racks, a reversing shaft located below said racks, a bed reciprocating gear carried by said reversing shaft, a pinion meshing with said bed reciprocating gear, and rotary movement imparting means, whereby, while retaining said pinion in mesh with said gear, engagement is effected in alternation between said racks and said pinion.

67. A printing press having a reciprocable bed carrying opposed racks, a reversing shaft located below said racks and carrying a primary reversing element, a bed reciprocating gear carried by said reversing shaft, a rack driving pinion oppositely rotated with respect to said reversing shaft and meshing with said bed reciprocating gear, and pinion revolving mechanism to revolve said pinion from engagement with one rack to engagement with another while retaining it in mesh with said bed reciprocating gear.

68. A printing press having a reciprocable bed carrying opposed racks, a reversing shaft located below said racks and having thereon a primary reversing element, a rack driving pinion rotated by said reversing shaft, and means to shift said pinion from engagement with one rack to engagement with an opposed rack by a rolling movement of said pinion, said pinion shifting means acting directly through said pinion to roll the same.

69. A printing press having a reciprocable bed carrying a plurality of racks, a reversing shaft located below said racks and having a primary reversing element, a bed reciprocating gear carried by said reversing shaft, a rack driving pinion meshing with said bed reciprocating gear, and means to revolve said pinion thereby to shift said pinion from engagement with one rack to engagement with another.

70. A printing press having a reciprocable bed carrying a plurality of racks, a reversing shaft located below said racks and having a primary reversing element, a bed reciprocating gear carried by said reversing shaft, a pinion meshing with said bed reciprocating gear, and pinion revolving mechanism acting thereby to shift said pinion from engagement with one rack to engagement with another.

71. A printing press having a reciprocable bed carrying a plurality of racks, a reversing shaft located below said racks and having thereon a primary reversing element, a bed reciprocating gear carried by said reversing shaft, a rack driving pinion meshing with said bed reciprocating gear, and means to shift said pinion from engagement with one rack to engagement with another rack by a rolling movement of the pinion.

72. A printing press having a reciprocable

- bed carrying a plurality of racks, a reversing shaft located below said racks and having thereon a primary reversing element, a bed reciprocating gear carried by said reversing shaft, a rack driving pinion meshing with said gear, and means to move said pinion in an arc about a predetermined center from engagement with one rack to engagement with another rack.
- 10 73. A printing press having a reciprocable bed carrying a plurality of racks, a reversing shaft located below said racks and having thereon a primary reversing element, a bed reciprocating gear carried by said reversing shaft, a rack driving pinion meshing with said gear, and means to shift said pinion from engagement with one rack to engagement with another rack by a rolling movement of the pinion, while maintaining the pinion in mesh with said gear.
- 15 74. A printing press having a reciprocable bed carrying a plurality of racks, a reversing shaft located below said racks and having thereon a primary reversing element, a bed reciprocating gear carried by said reversing shaft, a rack driving pinion meshing with said gear, and means to revolve said pinion, thereby to shift said pinion from engagement with one rack to engagement with another rack, while maintaining it in mesh with said gear.
- 20 75. A printing press having a reciprocable bed carrying a plurality of racks, a reversing shaft located below said racks and having thereon a primary reversing element, a rack driving pinion rotated by said reversing shaft and having means to revolve said pinion, thereby to shift said pinion from engagement with one rack to engagement with another rack, said pinion revolving means acting directly through said pinion to shift the same.
- 25 76. A printing press having a reciprocable bed carrying a plurality of racks, a reversing shaft located below said racks and having thereon a primary reversing element, a rack driving pinion rotated by said reversing shaft, and means to move said pinion in an arc about said reversing shaft as a center from engagement with one rack to engagement with another rack.
- 30 77. A printing press having a reciprocable bed carrying opposed racks, a reversing shaft, an impression cylinder having a gear thereon, said reversing shaft carrying a gear in mesh with the gear of the said impression cylinder, a primary reversing member upon said reversing shaft, a bed reciprocating gear upon said reversing shaft between said primary reversing member and said gear in mesh with the impression cylinder, a rack driving pinion meshing with said bed reciprocating gear, and means to impart relative movement to said pinion and said racks, whereby the racks may be engaged with said pinion alternately.
- 35 78. A printing press having a reciprocable bed carrying opposed racks, a reversing shaft, an impression cylinder having a gear thereon, said reversing shaft carrying a gear in mesh with the gear of the said impression cylinder, a primary reversing member upon said reversing shaft, a bed reciprocating gear upon said reversing shaft between said primary reversing member and said gear in mesh with the impression cylinder gear, a rack driving pinion meshing with said bed reciprocating gear, and means to elevate and depress said pinion thereby to bring it into alternate engagement with said opposed racks.
- 40 79. A printing press having a reciprocable bed carrying opposed racks, a reversing shaft located below said racks and having thereon a primary reversing element, a bell crank lever concentric with said reversing shaft, a pinion carried by said bell crank lever, and means to actuate said lever thereby to swing said pinion from engagement with one rack to engagement with an opposed rack.
- 45 80. A printing press having a reciprocable bed carrying racks, a reversing shaft below said racks and having thereon a primary reversing element, a lever concentric with said shaft, a pinion carried by said lever and means to actuate said lever, thereby to move said pinion from engagement with one rack to engagement with another opposed rack.
- 50 81. A printing press having a reciprocable bed carrying rack mechanism, a rotating shaft located below such rack mechanism and having thereon a primary reversing element, bearings wherein said shaft is maintained in fixed alinement, a rack driving pinion, a gear on said shaft wherewith said pinion is in mesh, and means to move said pinion in an arc in a vertical plane, whereby said pinion is caused to mesh with said rack mechanism to drive the same.
- 55 82. A printing press having a reciprocable bed and one or more racks operatively connected thereto, a rotating shaft, a gear mounted upon said shaft, a rack driving pinion meshing with said gear, an arm carrying said pinion, and means to move said pinion, so that the same periodically engages with said rack or racks, said pinion meshing with said gear upon said shaft eccentrically mounted upon said reversing shaft and reversing gears operatively connected to said eccentricities and adapted alternately to be brought into driving relation to said bed to reverse the movement thereof at the end of each stroke.
- 60 83. In a printing press comprising among its elements a bed and rack, a reversing shaft, a gear wheel upon said reversing shaft, a pinion meshing with said gear wheel, a lever concentric with said reversing shaft

- and carrying said pinion, and means for oscillating said lever to cause said pinion to mesh with the said rack to drive the same eccentrics mounted upon said reversing shaft 5 and reversing gears operatively connected to said eccentrics and adapted alternately to be brought into driving relation to said bed to reverse the movement thereof at the end of each stroke.
- 10 84. In a printing press comprising among its elements a bed and rack, a reversing shaft, a gear wheel upon said reversing shaft, a pinion meshing with said gear wheel, a lever concentric with the said reversing shaft and carrying said pinion, and means for oscillating said lever so as to reciprocate said pinion in a vertical plane eccentrics mounted upon said reversing shaft and reversing gears operatively connected 15 to said eccentrics and adapted alternately to be brought into driving relation to said bed to reverse the movement thereof at the end of each stroke.
- 15 85. In a printing press comprising among its elements a bed, opposed racks facing each other, a rotating shaft below said racks and having thereon a primary reversing element, a gear wheel upon said rotating shaft, a pinion meshing with said gear wheel, a bell 20 crank lever concentric with said rotating shaft and carrying said pinion, and means for oscillating said lever to cause said pinion to mesh with the said rack mechanism to drive the same.
- 25 86. In a printing press comprising among its elements a bed and rack, a rotating shaft having reversing eccentrics thereon, mechanism coöperating with said reversing eccentrics, a gear wheel upon said rotating 30 shaft, a pinion meshing with said gear wheel,
- a lever concentric with the said rotating shaft and carrying said pinion, and means for oscillating said lever so as to reciprocate said pinion in a vertical plane.
87. A printing press having a reciprocable 45 bed carrying opposed racks, a reversing shaft located below said racks and having thereon a primary reversing element, a pinion, means carrying said pinion a gear on said shaft wherewith said pinion meshes, 50 and mechanism to actuate said pinion carrying means, thereby to swing said pinion from engagement with one rack to engagement with an opposed rack.
88. A printing press comprising an impression cylinder having a gear, a reciprocable bed carrying a plurality of opposed racks, a reversing shaft below said racks and having a gear in mesh with said impression cylinder gear, a bed reciprocating gear upon 60 said reversing shaft, a rack driving pinion in mesh with said bed reciprocating gear, pinion shifting mechanism to shift said pinion into alternate engagement with said opposed racks while maintaining it in mesh 65 with said bed reciprocating gear, and reversing means operatively connected to said reversing shaft and adapted alternately to be brought into driving relation to said bed to reverse the movement thereof at the end 70 of each stroke.

In testimony whereof, we have signed our names to this specification, in the presence of two subscribing witnesses.

WILLIS K. HODGMAN.
BICKNELL HALL.
